(57) **CLAIM**

The ornamental design for a tank for water closet, as shown and described.

DESCRIPTION

In a preferred embodiment, the nature of this product is as a water reservoir for a water closet.

FIG. 1 is a left, top, front perspective view of a tank for water closet embodying my new design;

FIG. 2 is a front elevational view thereof;

FIG. 3 is a left side elevational view thereof, the right side elevational view being a mirror image of the left side shown;

FIG. 4 is a rear elevational view thereof;

FIG. 5 is a top plan view thereof;

FIG. 6 is a bottom plan view thereof; and,

FIG. 7 is a cross-sectional view thereof taken along line 7—7 of FIG. 2.

The broken line representations of holes in FIGS. 1 and 4—7 are for the purpose of illustration only, and form no part of the claimed design.
